SULFUR REMOVAL FROM CARBONACEOUS SOLIDS

William G. Toland, San Rafael, Calif., assignor to California Research Corporation, San Francisco, Calif., a corporation of Delaware
No Drawing. Filed May 26, 1960, Ser. No. 31,794
12 Claims. (Cl. 134—36)

This invention relates to a process for removing sulfur from sulfur-containing carbonaceous solids including sulfocarbon-type reactor deposits, and for weakening and removing said deposits from equipment wherein they are located.

In certain refinery and chemical processes, it is known that reactor fouling caused by steady accumulations of sulfur-containing carbonaceous reactor deposits imposes severe limitations on process operation, results in appreciable volume loss in expensive reactors, increases pressure drop, and is extremely detrimental in other significant respects.

The sulfur-containing carbonaceous solids referred to herein include generally all carbonaceous solids containing sulfur; however, the process of the present invention is particularly valuable in removing from equipment deposits of the types of sulfur-containing carbonaceous solids known as sulfocarbons. Sulfocarbons are well known in the art. For certain purposes other than as equipment deposits sulfocarbons have utility in themselves, and are manufactured especially for these uses. The chemical composition, characteristics and methods of preparation of various sulfocarbons are disclosed in various United States patents, for example Gamson U.S. Patents 2,447,005, 2,447,006, 2,525,343, 2,539,187, 2,539,188 and 2,569,095. These patents indicate that the sulfocarbons with which they are particularly concerned have carbon contents ranging from 47 to 90 weight percent, sulfur contents ranging from 6 to 50 weight percent, hydrogen contents ranging from .1 to 4 weight percent, and contain minor amounts of such other constituents as oxygen and ash. The patents indicate that the sulfocarbons with which they are concerned comprise sulfur, carbon and hydrogen in chemical combination. Where sulfocarbons of the type referred to in the patents occur as deposits in equipment, they can be readily removed by the process of the present invention, pursuant to which the sulfocarbons are weakened by removal of sulfur therefrom and thus are rendered amenable to physical destruction.

Frequently, sulfocarbon-type equipment deposits resulting from sustained operation of various items of equipment in the chemical process industries contain even higher percentages of sulfur than the sulfocarbons with which the aforementioned patents are concerned. For example, it has been found that sulfocarbon-type deposits in reactors in isophthalic plants of the type discussed hereinafter sometimes contain up to about 85 weight percent sulfur, together with around 1 weight percent hydrogen, the balance mainly consisting of carbon. However, a large amount of the sulfur content of these deposits—often more than 50 weight percent of the sulfur content—frequently is in the form of free sulfur, with the remainder being combined sulfur as in the sulfocarbons referred to in the patents hereinabove discussed. The remaining combined sulfur therefore often is present in approximately the same amounts as in the cited patents. The process of the present invention has been found to be effective in removing from the sulfocarbon-type deposits large amounts of both free and combined sulfur.

It is well known that the sulfocarbon-type deposits referred to above are extremely difficult to cope with in that they are insoluble and intractable, and when de-

2

posited in reactors during process operation cannot be removed in order to restore reactor volume and efficient process operation by methods known heretofore, except by plant shut-down, equipment dismantling, and manual destruction of the solids masses.

In view of the foregoing, it would be desirable if a simple and efficient process were available for removing sulfocarbon-type reactor deposits in a minimum period of time without the necessity for reactor dismantling or prolonged plant shut-down.

The foregoing desirable objects are fully obtainable with the process of the present invention, as will be described in more detail below. Sulfocarbon-type reactor deposits may be treated by the process of the present invention to place them in a more readily transportable form. The reactor deposits are changed in composition and structure in a manner that removes a portion of them in a gaseous form and renders the remaining portion amenable to easy physical removal by subsequent process steps.

In accordance with the present invention, there is provided a process for removing sulfur from sulfur-containing carbonaceous solids by contacting said solids with hydrogen in the presence of a material selected from the group consisting of water and hydrocarbons. Further, in accordance with the present invention, sulfur is removed from sulfur-containing carbonaceous solid reactor deposits built up during normal operation of a reactor which comprises discontinuing normal operation of said reactor and contacting said deposits in said reactor with hydrogen and the water and/or hydrocarbons. Still further, in accordance with the present invention, the process desirably is carried out at an elevated temperature and pressure and, when applied to reactor deposit removal, at least two cycles of alternate pressure steaming and depressuring of said reactor desirably applied to the reactor deposits following contacting of said deposits with said material and hydrogen.

The reactor deposit removal aspect of the present invention may be better understood from the following description of a specific embodiment of the invention, namely, the removal of sulfocarbon-type deposits from a reactor in a plant for producing isophthalic acid. Recent processes have been developed for producing isophthalic acid which involve oxidation of xylenes by an oxidizing medium comprising sulfur or a sulfur species. Examples of such oxidations include: (a) sulfate oxidation of a xylene using an aqueous ammonium sulfate oxidizing medium and a hydrogen sulfide reaction initiator to produce the corresponding phthalic acid as disclosed, for example, in U.S. Patent 2,722,549; (b) sulfur oxidation of a xylene using sulfur and water to produce the corresponding phthalic acid, as disclosed in U.S. Patent 2,903,480; and (c) sulfur-ammonia oxidation of a xylene using sulfur and ammonia to produce the corresponding phthalic acid, as disclosed in U.S. Patent 2,610,980. The foregoing reactions and other similar oxidation processes employ reaction mechanisms that inevitably result in the production of various by-products, for example, thioacids and sulfur compounds, that enter into side reactions, such as polymerization, leading to the production of heavy deposits of sulfocarbons on reactor interiors. Such deposits build up in a steady accumulation during reactor operation and seriously reduce reactor volume, disturb pressure balances, and reduce reactor efficiency. These insoluble and intractable deposits heretofore have resisted all efforts at their removal other than use of the most drastic expedients such as plant shut-down for prolonged periods of time, reactor dismantling, and chiseling out of the deposits.

In accordance with the present invention, the reactor deposits referred to in the preceding paragraph may be

removed simply, quickly, and efficiently at low cost. The following example illustrates a specific embodiment of the process of the invention.

EXAMPLE 1

A commercial isophthalic acid plant reactor having an original volume of about 700 cubic feet and containing sulfocarbon deposits built up by steady accumulation during sulfate oxidation of xylenes to phthalic acids was determined by tests to contain sufficient sulfocarbon deposits, amounting to thousands of pounds, to have reduced the reactor volume by over 35% from the original volume at the beginning of process operation. Process operation was discontinued and the sulfocarbon deposits in the reactor were subjected to a treatment with a combination of water and a gas comprising 75 volume percent hydrogen at a temperature of 640° F. and 3000 p.s.i.g. for a period of only 40 hours, the water being supplied to the reactor during this period at a rate ranging from 1000 to 2500 barrels per day and the gas being supplied to the reactor during this period at a rate of from about 50 to 165 standard cubic feet per minute. It was found that operation under these conditions produced a reaction involving the sulfocarbon deposits and the feed water and the gas that resulted in a reactor off-gas containing unreacted hydrogen, and large quantities of hydrogen sulfide. Analyses of the off-gas showed that during the 40-hour period almost 2000 pounds of sulfur had been removed from the reactor deposits in the form of hydrogen sulfide. This corresponded to about 15% of the calculated amount of sulfocarbon in the reactor. Following the 40-hour period, the reactor was cyclically subjected to steam at 500 p.s.i.g. followed by rapid depressuring. Such an operation would have had little or no effect on the tough, insoluble and intractable sulfocarbons comprising the original reactor deposits prior to the water and hydrogen treatment; however, after the water and hydrogen treatment had been performed, it was found that the alternate high pressure steam and depressuring operations flushed from the reactor amazingly large quantities of a powdery black solid material. This material was a substantial proportion of the remaining sulfocarbon deposit that had been made fragile and amenable to physical removal by virtue of the sulfur removal accomplished during the hydrogen and water treatment. The combined hydrogen and water treatment and the alternate high pressure steam and depressuring operations resulted in reducing the unavailable reactor volume space occupied by sulfocarbon-type deposits from 37% of the total to 1.5% of the total, a highly surprising and unexpected result in view of the long-standing reactor deposit problem in the industry, in view of the relative simplicity of the process used in the example.

Those skilled in the art will realize that many plant conditions and operating factors such as the type of process leading to the deposits, the duration of process operation before deposit removal, the reactor size, etc., will influence the optimum operating conditions for the process of the present invention, including water and gas feed rates, reaction temperature and pressure and steam pressure applicable to the process. However, with the foregoing specific embodiment in mind and with the following remarks, those skilled in the art will be able to determine with relative ease the necessary conditions under which the present process should be operated in their own situations. Generally speaking, it is preferable that the water and hydrogen treatment of the solid reactor deposits be conducted at from about 500° to 1000° F. and from about 1500 to 5000 p.s.i.g. The amounts of hydrogen and water required for satisfactory results depends upon the composition and extent of the deposits, upon the treating temperature and pressure and upon the time of treatment. For deposits in commercial plant reactors such as the isophthalic plant referred to herein, the deposit removal process preferably is conducted as a continuous operation at a water feed rate of 0.5 to 10 barrels

per day per cubic foot of original reactor volume and a hydrogen feed rate, based on 100% hydrogen, of 0.01 to 1.0 standard cubic foot per minute per cubic foot of original reactor volume. It is clear that these figures are guides only and that a man skilled in the art being aware by the present disclosure of the unexpected efficacy of the present process and the advantages derivable therefrom may operate within the above ranges or may possibly find that operation outside some of those ranges may be expedient for his particular situation.

Variations on the foregoing process are possible. For example, it may be desirable in some situations to conduct the water and hydrogen treatment portion of the process with the water in liquid phase, while in other situations vapor phase may be desirable. In other situations, it may be desirable to begin the operation with the water in liquid phase and, following a partial removal of sulfur from the reactor deposits, to complete the operation with the water in vapor phase. In this connection, it has been noted that a relatively high reaction rate, as determined by analyses of the reactor off-gas, may be expected during the initial stages of the process, probably because of more rapid reaction of the free sulfur in the deposits. Following the reaction of the free sulfur, the water and hydrogen can more vigorously attack the combined sulfur in the deposits, upon which the deposits begin to weaken with the attendant danger that with water in liquid phase portions of the weakened deposits may break away and be carried with the water into equipment piping. Such a happening might necessitate shutdowns if the deposit portions plug the lines. Accordingly, a particularly desirable operation would be one wherein the initial stage of the water and hydrogen treatment is conducted with the water in liquid phase until the free sulfur in the deposits has been removed, after which the remaining treatment is conducted with the water in vapor phase. A particularly desirable combination of hydrogen and water feed rates to the process is one in which the hydrogen feed rate will be just enough to saturate the water with hydrogen at operating temperature and pressure.

While the precise duration of the water and hydrogen treatment step may vary widely, those skilled in the art will easily be able to determine when the treatment has progressed sufficiently for their purposes, for example, by making a continuous analysis of the reactor off-gas.

The examples in the following table will serve to further illustrate the process of the present invention. In each of the examples the sulfocarbon used was obtained from commercial isophthalic acid plant reactors and subjected to treatment pursuant to the process of the present invention in controlled batch-type laboratory runs.

Table I

Example	2	3	4	5	6
Charge:					
Sulfocarbon, Wt. g.—					
From Reactor A	50	12.5	12.5	12.5	12.5
From Reactor B	50	12.5	12.5	12.5	12.5
Composition, percent:					
C	15.3	19.3	19.3	19.3	19.3
H	1.1	1.1	1.1	1.1	1.1
S	82.3	82.3	82.3	82.3	82.3
Water, cc.	1,000	1,000	None	500	250
Xylene, cc.	None	None	1,000	500	None
Hydrogen, p.s.i.g., cold	1,000	750	700	700	650
Conditions:					
Temperature, ° F.	630-40	630-40	640-50	635-40	640
Pressure, max. p.s.i.g.	4,025	3,725	1,825	3,700	2,600
Time, min.	70	180	150	160	180
Products:					
Sulfocarbon, Wt. g.—	21.5	4.2	4.2	2.4	4.8
Composition, Percent—					
C	52.2	43.0	51.5	33.6	-----
H	2.5	1.6	2.0	1.3	-----
S	37.0	32.5	34.7	32.9	-----
Ash				36.3	-----
Calculations:					
Percent Sulfocarbon Removed	78.5	83.2	83.2	90.4	80.9

From the above table it may be seen that by the process of the present invention, not only was free sulfur removed from the sulfocarbon-type deposits, but also carbon, hydrogen, and some combined sulfur. For instance, in run 3 of the total sulfocarbon charged, 56% of the carbon disappeared, 76% of the hydrogen, and 93% of the sulfur. Where the highest portions of sulfocarbon were removed, the ash content of the residue became greater. For example, in run 5, the residue contained 36.3% ash. In most cases a white solid sublimed from the residues which was proven to be thianthrene. In run 6, where the vapor phase was withdrawn from the reactor at reaction temperature, this thianthrene condensed in the H_2S scrubber. It represented up to perhaps 10% of the residue. Gaseous products consisted largely of hydrogen and hydrogen sulfide.

The pressure of hydrogen used in the process of the present invention does not appear to be particularly critical. This is borne out by the examples in Table I, above, in which the amount of residue obtained was relatively consistent over a wide range of hydrogen pressure. Recycling of residue with fresh hydrogen failed to decrease the weight of the residue appreciably.

While water is the preferred medium for use with the hydrogen in the process of the present invention, mainly because of its availability and low cost, hydrocarbons that are substantially inert under the conditions used in the process may be used in lieu of water or in conjunction with water. The hydrocarbons tend to have a useful solubilizing effect on the sulfur contained in the sulfocarbons; the xylenes are examples of hydrocarbons that are especially effective in this regard. It will be noted from the above table that xylene was used instead of water in Example 4 and in that example 83.2% of the sulfocarbon was removed.

Hydrocarbons are useful in the process not only because of their solubilizing effect on the sulfur contained in the sulfocarbons, but because they tend to act as swelling agents for one or more of the constituents of the sulfocarbons, and thus facilitate the loosening of the sulfocarbons from equipment and facilitate the weakening of the sulfocarbons themselves. Water is useful in the process not only because of its solubilizing effect on the sulfur contained in the sulfocarbons, but because it tends to hydrolyze some of the sulfur compounds present in the sulfocarbons, thereby further aiding in weakening the sulfocarbons. Both water and hydrocarbons have utility in the process as carrier media for transporting portions of the dislodged sulfocarbon deposits and materials removed from the deposits.

Examples of hydrocarbons that may be used alone or in combination in the present process include normally liquid and normally gaseous paraffins, aromatics and naphthenes, including pentane, butane, cyclohexane, the xylenes, benzene, toluene and decalin, as well as petroleum distillate cuts, all other functionally equivalent hydrocarbons that are inert under the conditions of the process, and combinations of the foregoing. Whether the foregoing hydrocarbons are used alone or in combination, water may be present in any proportion. Where hydrocarbons are used in lieu of water or in conjunction with water, normally liquid hydrocarbons, and preferably the aromatic hydrocarbons, are most preferred.

I claim:

1. A process for removing sulfur from sulfur-containing carbonaceous solids, which comprises contacting said material with hydrogen in the presence of a material selected from the group consisting of water and inert normally liquid hydrocarbons at an elevated temperature and pressure.

2. A process for removing sulfur from a sulfur-containing carbonaceous solid, which comprises contacting said solid with hydrogen in the presence of water at an elevated temperature and pressure.
3. A process as described in claim 2, wherein said water is in the vapor phase during said contacting.
4. A process for removing sulfur from sulfur-containing carbonaceous solid reactor deposits built up during normal operation of a reactor, which comprises discontinuing normal operation of said reactor, and contacting said deposits in said reactor with hydrogen and a material selected from the group consisting of water and inert normally liquid hydrocarbons at an elevated temperature and pressure.
5. A process for removing sulfur from carbon-containing reactor deposits built up during normal operation of a reactor, which comprises discontinuing normal operation of said reactor, contacting said deposits in said reactor with water and hydrogen with at least a portion of said water in liquid phase until a substantial proportion of sulfur has been removed from said deposits, adjusting the process conditions to force said water into vapor phase, and continuing said contacting with said water in vapor phase until a further substantial proportion of sulfur has been removed from said deposits.
6. A process as in claim 5, with the additional steps of at least two cycles of alternate pressure steaming and depressuring of said reactor following contacting of said solids with water and hydrogen gas.
7. A process as in claim 6, carried out in the added presence of an inert normally liquid hydrocarbon.
8. A process for removing sulfur from carbon-containing reactor deposits built up during normal operation of a reactor, which comprises discontinuing normal operation of said reactor, contacting said deposits in said reactor with an inert normally liquid hydrocarbon and hydrogen with at least a portion of said hydrocarbon in liquid phase until a substantial proportion of sulfur has been removed from said deposits, adjusting the process conditions to force said hydrocarbon into vapor phase, and continuing said contacting with said hydrocarbon in vapor phase until a further substantial proportion of sulfur has been removed from said deposits.
9. A process as in claim 8, wherein said hydrocarbon is xylene.
10. A process as in claim 8, with the additional steps of at least two cycles of alternate pressure vaporizing and depressuring of said reactor following contacting of said solids with said inert hydrocarbon and hydrogen gas.
11. A process for removing sulfur from a sulfur-containing carbonaceous solid which comprises contacting said solid with hydrogen in the presence of an inert normally liquid hydrocarbon at an elevated temperature and pressure.
12. A process as in claim 11, wherein said hydrocarbon is xylene.
